UNITED STATES PATENT OFFICE.

CHARLES H. HOWLAND-SHEARMAN, OF INDIANAPOLIS, INDIANA.

JACK.

1,400,605.

Specification of Letters Patent. Patented Dec. 20, 1921.

Application filed October 21, 1920. Serial No. 418,454.

To all whom it may concern:

Be it known that I, CHARLES H. HOWLAND-SHEARMAN, a citizen of the United States, residing at Indianapolis, in the county of Marion and State of Indiana, have invented certain new and useful Improvements in Jacks, of which the following is a specification.

The objects of my invention are as follows: first, to provide a mechanism for jacks which shall be capable of exerting a power equal to that of the most powerful previous jacks of different construction, but of operating at much greater speed; second, to furnish a jack of sufficient compactness and of adequate power for the heaviest classes of service, so as to adapt it to be carried as a part of the regular equipment of motor-trucks, cabooses, wrecking-cars etc.; and third, to supply a form of jack adaptable to use in handling the parts of heavy machinery, in assembling-shops for emergency work in connection with cranes, and for similar requirements.

I accomplish the objects referred to by means of the mechanism illustrated in the accompanying drawings, in which—

Figure 1, is a side elevation of one of my jacks of the ten-ton capacity; Fig. 2, is a longitudinal section of the same jack shown in Fig. 1, taken on the line 2—2 Fig. 3 looking in the direction of the arrows, showing the general arrangement of the complete mechanism; Fig. 3 is a transverse sectional view, taken of the line 3—3 Fig. 2 looking in the direction of the arrows, showing in detail, the dash-pot mechanism and ram with the guides therefor and portions of the pawl-yoke, lifting-beam and walking-link constructions; Fig. 4 is a transverse sectional view of the same jack, taken on the line 4—4 Fig. 2 looking in the direction of the arrows, showing details of the primary tractor-levers, secondary tractor-levers, and lifting-beam, and illustrating the method of assembling the bifurcated frame, in which I prefer to house the mechanism of my invention for its protection against dirt and moisture; and Fig. 5 is a transverse sectional view, taken on the line 5—5 Fig. 2 looking in the direction of the arrows, showing details of the power-crank, connecting-link, primary tractor-levers, and lifting beam.

Similar numerals refer to similar parts throughout the several views.

Referring to Figs. 1, 2, and 5, 1 is the bi-

furcated frame of my jack, consisting of the two halves 2 and 3, each preferably machined and fitted tightly together with a cement in the joints for exclusion of injurious substances. A demountable handle as 4, is inserted in the socket 5 of the power-crank 6, pivoted on the fulcrum-pin 7, the threaded reductions on the ends of which are piercingly secured through the respective halves 60 2 and 3 of the frame 1 by nuts as 8 and 9, causing said fulcrum-pin to also function as a member for assembling said frame.

Referring to Figs. 2, 4 and 5, said power-crank 6 bears a slot 10, within which is articulated by the connecting-pin 11 the connecting-link 12, the opposite end of which link is commonly jointed by means of the knuckle-pin 13, between the lower end of the slotted suspension-arm 14, and the upper end 65 2 of the duplex delivery-arm 15 of the primary tractor levers 16, suspended upon the primary suspension-pin 17, and the reduced threaded ends of the latter pin are piercingly secured through the halves 2 and 3 of 70 the frame 1 by the respective nuts 18, 19, so as to also function as an assembling member for said frame. The lower end of said duplex delivery-arm 15 is commonly articulated by means of the secondary knuckle-pin 20 intermediately between the inner ends 75 of the suspension-arm 21 and delivery-arm 22 of the secondary tractor-levers 23 journaled on the secondary fulcrum-pin 24; the two halves of the lower end of said duplex 80 delivery-arm 15 of said primary tractor-levers 16 being spaced by the collar 25, for correct parallelism with said primary suspension arm 14, as especially shown in Fig. 4. The said secondary suspension-pin 24 85 likewise bears threaded reductions at its ends piercingly secured by nuts as 26, exterior to either half of the bifurcated frame, as indicated by Fig. 1.

By comparison of Figs. 2, 4, and 5 it will 100 be seen that while the halves of the duplex secondary suspension-arm 21 are checked closely contiguous to the inside face of the frame 1, inclosing between them the halves of the duplex secondary delivery arm 22, the 105 latter are in turn inclosed between the lower ends of the two halves of the duplex lifting-beam 27, between which they are spaced by the internal spacer 28 and to which they are articulated by the secondary delivery-pin 29. This arrangement enables the halves of 110 said duplex lifting-beam 27 to in turn be

closely cheeked up against thin washers as 30 close to the inner faces of the respective halves 2 and 3 of the bifurcated frame, through which the beam fulcrum-pin 31 is 5 piercingly secured by nuts 32, 33, so as to cause it to also function as an assembling member to said frame. Clearance openings 34 are provided on either half of the duplex lifting-beam 27 to permit the positioning 10 therethrough of the fixed fulcrum-pin 7 without motion interference therewith of said lifting-beam 27.

As indicated in Figs. 2 and 3, the inner end of the lifting-beam 27 is articulated by 15 the yoke-pin 35 to the duplex pawl-yoke 36 having secured therein the inner pawl-pin 37 on which is mounted the inner lifting-pawl 38 and the outer pawl-pin 39 on which is pivoted the outer lifting-pawl 40, respectively adapted to engage with the inner ratchet teeth 41, and outer ratchet teeth 42 on the ram 43, as especially indicated in Fig. 2. The inner spring-lug 44, contains the inner compression spring 45 which keeps the 25 inner lifting-pawl 38 normally in contact with said inner ratchet teeth 41, and the outer spring-lug 46 contains the outer compression spring 47 which keeps the outer lifting-pawl 40 normally in engagement 30 with the outer ratchet teeth 42. Both of said lugs are secured to the halves of the duplex lifting-beam 27 by cap screws as 48 in Fig. 3.

Referring to Figs. 1, 2, and 3, the inner sustaining pawl fulcrum-pin 49 having 35 mounted thereon the inner sustaining pawl 50 and the outer sustaining-pawl fulcrum-pin 51 having mounted thereon the outer sustaining-pawl 52 are piercingly secured through the respective halves 2 and 3 of the 40 frame by threaded reductions furnished with nuts as 53 Fig. 3 which also adapt said fulcra to act as members for assembling the frame. As indicated in Figs. 1 and 2, said inner sustaining-pawl 50 is normally kept in 45 contact with the inner ratchet teeth 41 of the ram 43 by a compression spring 54 contained in the lug 55 piercingly secured through both halves of the frame by bolts 56 having nuts 57; and said outer locking-pawl 52 is 50 normally kept in engagement with the outer ratchet teeth 42 by the compression spring 58 in the lug 59 piercingly secured through both halves of the bifurcated frame by the bolts 60 having nuts 61.

55 Referring to Fig. 2 the toggle-link 62 is journaled at its end in the toggle-pin 63, secured in the top of the outer lifting-ratchet 40, and is articulated at its inner end by the knuckle-pin 64 which commonly engages 60 with the inner end of the toggle-lever 65 jointed to the toggle-pin 66 secured near the top of the inner lifting-pawl 38. The purpose of this toggle mechanism is to release both said inner lifting-pawl 38 and outer 65 lifting-pawl 40 from engagement with the

respective inner ratchet-teeth 41 and outer ratchet-teeth 42 of the ram 43 and to lock the same out of engagement by depressing said toggle lever 65 so as to straighten the toggle as is done when it is desired to lower 70 a load resting upon said ram 43.

Referring to Figs. 2, 3, and 5, the power-crank 6 bears coextensively above the slot 10 the extension arm 67 having the slotted fork 68, which is adapted to receive the 75 walking-link 69. The demountable pin 70, is capable of being inserted in the end of said walking-link 69, and of engaging in the slotted fork 89 to articulate the members 80 when it is desired to operate said walking-link for lowering a load, but is withdrawn when operating the jack to lift a load. Said walking-link is single at the outer end, but becomes duplex after entering the jack, as shown in Fig. 3. The inner sustaining pawl 85 50, is provided with intermediate pins as 71 Figs. 2 and 3, engaging with the pulling slot 72 in said walking-link 69, and the sustaining pawl 52 is provided with intermediate pins 73 engaging within the pushing slot 90 74 in said walking-link.

As indicated in Figs. 2 and 3, the ram 43, within the frame 1, slides on either side between guides such as the upper guide 75, intermediate guide 76, and lower guide 77, coextensively formed within the bifurcated half-frame 2, and by an oppositely registering upper guide 78, intermediate guide 79, and lower guide 80, coextensively formed on the inside of the opposite half-frame 3, the 100 said guides being engaged by oppositely registering slots 81, 82, made in the sides of the ram 43.

Referring to Fig. 2, the function of said pushing and pulling slots 72, 74 with their 105 respective intermediate pins 71 and 73 may be exemplified thus: When lowering a load, a slight depression of the power-crank 6, first draws outward the walking-link 69, causing the intermediate pin 71 to withdraw the sustaining-pawl 50 from engagement with the ratchet-teeth 41, which teeth are positioned one-half pitch below the opposite ratchet-teeth 42, which therefore permits the ram 43 to drop one-half pitch, so 110 that the ratchet-teeth 42 rest upon the opposite sustaining-pawl 52. During this motion, the pushing slot 74 has overtaken said intermediate pin 73, but, as the sustaining-pawl 52 now snaps into engagement, said intermediate pin 73 again rests at the inner 115 end of said pushing slot 74, as shown in Fig. 2. When the power-crank 6 is now slightly lifted, it pushes said walking-link 69, and in so doing engages said intermediate pin 73, 120 and while the opposite pulling-slot 72 runs idle, pushes out from engagement with the outer ratchet-teeth 42 the outer sustaining-pawl 52, thus permitting the ram 43 to descend by the distance of one-half pitch of the 125 130

opposite inner ratchet-teeth 41, which returns the parts to the relative positions drawn in Fig. 2.

In order to prevent any injurious shock 5 being sustained when large loads of many tons are lowered on the ram 43 which might result in gradual injury to ratchet-teeth 41 and 42, I employ the following mechanism, as clearly illustrated in Figs. 2 and 3: The 10 dash-pot 83, bored into the lower end of the ram 43, has fitted therein the long dash-pot plunger 84, having a shouldered reduction 85 at the base thereof, fitting tightly within a bore in the base-boss 86, upon which rests 15 the butt 87 of the ram 43 when returned to the bottom of its stroke. An air orifice 88 near the top of said dash-pot 83 gives ingress and egress of air to the dash-pot. When a load is being raised the dash-pot 83 is steadily 20 filled with air through the air orifice 88, but when a load is being lowered by operation of the walking-link 69, as described in the previous paragraphs, the air in said dash-pot 83 is quickly compressed and acts 25 to cushion the descent of the ram 43 as the respective sustaining-pawls 50, 52 are released from engagement with the ratchet-teeth 41, 42 by said walking-link, thus permitting the ram and its load to have a cushioned 30 descent, as the compressed air very gradually escapes through the air-orifice 88, and so preserves the ratchet-teeth from injury and the load from shock.

Referring to Figs. 4 and 5 an intermediate 35 spacing sleeve 90 is employed on the beam fulcrum-pin 31 to laterally space the halves of the lifting lever 27, so that the same shall align parallel to the outer faces of the delivery-arm 22 of the secondary tractor-levers 40 23, thus laterally securing said halves of said lifting beam between said intermediate spacer and the thin washers 30, as clearly shown in Fig. 5.

The operation of my invention is as follows: Whenever the frame 1 has been seated 45 in any position such as on a road-bed, blocks or other base, and the jack has been slid with its ram 43 beneath the load to be raised, with the demountable pin 70 removed from the 50 walking-link 69, and the handle 4 inserted in the socket 5, and both the lifting-pawls and sustaining-pawls in engagement, the power-crank 6 is depressed by operation of said handle, the force imparted therefrom 55 transmitting through the connecting link 12, which, pulling upon the primary knuckle-pin 13, bends the straightened primary tractor-levers 16, sustained from the primary suspension-pin 17, and causes said tractor- 60 levers to exert in a straightened upward direction a greatly augmented pressure through the knuckle-pin 20, which bends the straightened secondary tractor-levers 23 sustained on the secondary suspension pin 24 and 65 causes said secondary tractor-levers to exert

a vastly intensified force through the secondary delivery-pin 29, which is transmitted around the fulcrum-pin 31, and through the lifting-beam 27 which thus converts this pulling effort into a powerful lifting effort 70 which is imparted through the yoke-pin 35 to the duplex pawl-yoke 36, and thence through the lifting-pawls 38 and 40, pivoted thereon, which pawls being staggered with the inner pawl 38 thereof one-half pitch in 75 advance of the outer pawl 40, causes each upward impulse of said yoke-pin from said lifting-beam to lift, by the space of one-half pitch of the ratchet-teeth 41 and 42, in alternation, the ram 43. As the respective 80 lifting-pawl 50 pivoted on the fulcrum-pins 49 and 52 pivoted on the fulcrum-pin 51 are also staggered with the inner thereof one-half pitch in advance of the outer thereof, they synchronously drop into place in 85 engagement with the respective ratchet-teeth 41 and 42, in alternation, as said ram 43 is raised by the amount of one-half tooth pitch, at each depression of the handle 4, and so sustains the load at every position of lift. 90

When it is desired to lower a load, the toggle-link 62 and toggle-lever 65 are straightened by depressing the latter until same are in a straight line, which disengages the lifting-pawl 38 from the ratchet-teeth 41 and the lifting-pawl 52 from the ratchet-teeth 42, leaving the load upheld exclusively by said sustaining-pawls 50 and 52. The demountable pin 70 is then inserted through the walking-link 69 and slotted 100 fork 68 of the power-crank 6, and the latter is very slightly oscillated, which causes the walking-link 69 to alternately push the inner sustaining-pawl 50 out of engagement with the inner ratchet-teeth 41, and the outer 105 sustaining-pawl 52 out of engagement with the outer ratchet-teeth 42, thus lowering the load at each such movement by the distance of one-half pitch of said teeth, the descent being meanwhile cushioned by the air imprisoned in the dash-pot 83 (Fig. 3), over the dash-pot plunger 84. It will be noted that the constant action of the powerful compression springs 54 engaging the inner sustaining-pawl 50 and 58 engaging the sus- 110

taining-pawl 52, in connection with the accurately spaced distance between said pawls and between the pushing slot 72 containing the intermediate pin 71 the pulling-slot 74 having the intermediate pin 73 is such that 115 it is impossible for the parts to ever occupy any position wherein one of the said two pawls is not in secure engagement with its adjacent ratchet-teeth, so that consequently the ram 43 may not under any circumstances 120 slip past said pawls and cause a load on the ram 43 to drop suddenly on the dash-pot 83.

Having thus described my invention, I claim:

1. Combined in a jack a frame; a manu- 130

- ally operable power-crank, pivoted in said frame; and inter-articulated dual sets of tractor-levers, adapted to be actuated by said power-crank, substantially as described. 65
5. 2. Combined in a jack a frame; a manually operable power-crank pivoted in said frame, provided with a connecting-link; a primary set of tractor-levers suspensionally pivoted in said frame, adapted to be actuated by said power-crank and link; a secondary set of tractor-levers suspensionally pivoted in said frame, having a knuckle-pin thereof articulated to the delivery-pin of said primary set of tractor-levers, adapted 70
- 10 to be actuated by said primary set of tractor levers; and lifting members, adapted to be actuated by said secondary set of tractor-levers, substantially as described. 75
- 15 3. Combined in a jack a frame; a manually operable power-crank pivoted in said frame, provided with a connecting-link; a primary set of tractor-levers suspensionally pivoted in said frame, having the knuckle-pin thereof articulated to the delivery-pin of 80
- 20 said primary set of tractor-levers, adapted to be actuated by said primary set of tractor-levers; a lifting-beam pivoted in said frame adapted to be actuated by said secondary set of tractor-levers; and a ram 85
- 25 adapted to be actuated by said lifting-beam, substantially as described. 90
- 30 4. Combined in a jack a frame; a manually operable lifting linkage pivoted in said frame; a lifting yoke having pivoted thereon duplex lifting-pawls, adapted to be actuated by said manually operable lifting linkage; a ram slidably guided in said frame provided with ratchets adapted to be engaged by said lifting-pawls; and, pivotally 95
- 35 fixed in said frame, duplex lifting-pawls 100
- 40 adapted to engage the ratchets on said ram adapted to sustainingly engage the ratchets on said ram as the latter is actuated by said lifting-pawls. 105
- 45 5. Combined in a jack a frame; a manually operable power-link provided with a connecting-link; inter-articulated primary and secondary sets of tractor-levers, each 110
- 50 set being suspensionally pivoted in said frame, capable of being actuated by said power-crank and link; a duplex lifting-beam, pivoted in said frame, capable of being operated by the action of the secondary of said sets of tractor-levers; a duplex pawl- 115
- 55 yoke pivoted within said duplex lifting-beam, having pivoted thereon spring actuating lifting-pawls; and a ram slidably guided in said frame having thereon ratchets adapted to be engaged by said lifting-pawls, substantially as described. 120
- 60 6. Combined in a jack, a frame; a manually operable lifting-linkage, comprising suspensionally pivoted, interarticulated tractor-levers and a lifting-beam adapted to
- be actuated thereby; duplex pawl-yoke, pivoted to said lifting-beam having pivoted thereon duplex spring actuated lifting-pawls; a ram slidably guided in said frame, provided with ratchets adapted to be engaged by said duplex lifting-pawls; and pivotally fixed in said frame, duplex spring actuating sustaining-pawls, adapted to sustainingly engage said ratchets on said ram, as the latter is actuated by said lifting-pawls; and a self-contained pneumatic dash-pot in said ram, having the plunger thereof sustained by said frame, adapted to cushion the motion of said ram during the retraction thereof, substantially as described. 75
7. Combined in a jack, a frame; a manually operable lifting-linkage, comprising suspensionally pivoted, inter-articulated tractor-levers and a lifting-beam adapted to be actuated thereby; duplex pawl-yoke, pivoted to said lifting-beam having pivoted thereon duplex spring actuated lifting-pawls; a ram slidably guided in said frame, provided with ratchets adapted to be engaged by said duplex spring actuating sustaining-pawls, adapted to be engaged by said duplex lifting-pawls; pivotally fixed in said frame, duplex spring actuating sustaining-pawls, adapted to sustainingly engage said ratchets on said ram, as the latter is actuated by said lifting-pawls; and a self-contained pneumatic dash-pot in said ram, having the plunger thereof sustained by said frame, adapted to cushion the motion of said ram during the retraction thereof, substantially as described. 85
8. Combined in a jack, a frame; a manually operable lifting-linkage, comprising suspensionally pivoted, inter-articulated tractor-levers and a lifting-beam adapted to be actuated thereby; duplex pawl-yoke, pivoted to said lifting-beam having pivoted thereon duplex spring actuated lifting-pawls; a ram slidably guided in said frame, provided with ratchets adapted to be engaged by said duplex spring actuating sustaining-pawls, adapted to be engaged by said duplex lifting-pawls; pivotally fixed in said frame, duplex spring actuating sustaining-pawls, adapted to sustainingly engage said ratchets on said ram, as the latter is actuated by said lifting-pawls; and a self-contained pneumatic dash-pot in said ram, having the plunger thereof sustained by said frame, adapted to cushion the motion of said ram during the retraction thereof, substantially as described. 95
9. Combined in a jack, a frame; a manually operable lifting-linkage, comprising suspensionally pivoted, inter-articulated tractor-levers and a lifting-beam adapted to be actuated thereby; duplex pawl-yoke, pivoted to said lifting-beam having pivoted thereon duplex spring actuated lifting-pawls; a ram slidably guided in said frame, provided with ratchets adapted to be engaged by said duplex spring actuating sustaining-pawls, adapted to be engaged by said duplex lifting-pawls; pivotally fixed in said frame, duplex spring actuating sustaining-pawls, adapted to sustainingly engage said ratchets on said ram, as the latter is actuated by said lifting-pawls; and a self-contained pneumatic dash-pot in said ram, having the plunger thereof sustained by said frame, adapted to cushion the motion of said ram during the retraction thereof, substantially as described. 105
10. Combined in a jack, a frame; a manually operable lifting-linkage, comprising suspensionally pivoted, inter-articulated tractor-levers and a lifting-beam adapted to be actuated thereby; duplex pawl-yoke, pivoted to said lifting-beam having pivoted thereon duplex spring actuated lifting-pawls; a ram slidably guided in said frame, provided with ratchets adapted to be engaged by said duplex spring actuating sustaining-pawls, adapted to be engaged by said duplex lifting-pawls; pivotally fixed in said frame, duplex spring actuating sustaining-pawls, adapted to sustainingly engage said ratchets on said ram, as the latter is actuated by said lifting-pawls; and a self-contained pneumatic dash-pot in said ram, having the plunger thereof sustained by said frame, adapted to cushion the motion of said ram during the retraction thereof, substantially as described. 110
11. Combined in a jack, a frame; a manually operable lifting-linkage, comprising suspensionally pivoted, inter-articulated tractor-levers and a lifting-beam adapted to be actuated thereby; duplex pawl-yoke, pivoted to said lifting-beam having pivoted thereon duplex spring actuated lifting-pawls; a ram slidably guided in said frame, provided with ratchets adapted to be engaged by said duplex spring actuating sustaining-pawls, adapted to be engaged by said duplex lifting-pawls; pivotally fixed in said frame, duplex spring actuating sustaining-pawls, adapted to sustainingly engage said ratchets on said ram, as the latter is actuated by said lifting-pawls; and a self-contained pneumatic dash-pot in said ram, having the plunger thereof sustained by said frame, adapted to cushion the motion of said ram during the retraction thereof, substantially as described. 115
12. Combined in a jack, a frame; a manually operable lifting-linkage, comprising suspensionally pivoted, inter-articulated tractor-levers and a lifting-beam adapted to be actuated thereby; duplex pawl-yoke, pivoted to said lifting-beam having pivoted thereon duplex spring actuated lifting-pawls; a ram slidably guided in said frame, provided with ratchets adapted to be engaged by said duplex spring actuating sustaining-pawls, adapted to be engaged by said duplex lifting-pawls; pivotally fixed in said frame, duplex spring actuating sustaining-pawls, adapted to sustainingly engage said ratchets on said ram, as the latter is actuated by said lifting-pawls; and a self-contained pneumatic dash-pot in said ram, having the plunger thereof sustained by said frame, adapted to cushion the motion of said ram during the retraction thereof, substantially as described. 120

In witness whereof, I have hereunto set my hand and seal at Indianapolis, Indiana, this 16th day of October, A. D. nineteen hundred and twenty.
